UNITED STATES PATENT OFFICE.

FITCH C. IRVING, OF BROOKLYN, NEW YORK.

TRIANGLE PAD.

Application filed May 25, 1927. Serial No. 194,103.

This invention relates to triangle pads and has for an object to provide an improved construction wherein the pad may be readily applied or removed and when applied and in use may be readily positioned to operate or to hang loosely out of the way.

Another object of the invention is to provide a triangle pad which has a strong leather or other body with one or more surface members mounted thereon and stitched with lines of stitching arranged in parallel rows for permitting ready bending.

A further object, more specifically, is to provide a triangle pad wherein bed cloth is used on top and bottom and a strong leather or other body provided centrally with the body surrounding part of the triangle while the cloth contacts with the balls and also with the cloth of the table when the device is in use.

In the accompanying drawing—

Figure 1 is a fragmentary top plan view of a pool table with a triangle having a pad embodying the invention applied thereto shown in position on the table for receiving balls.

Figure 2 is an enlarged fragmentary sectional view through part of a triangle with an embodiment of the invention applied thereto.

Figure 3 is a view similar to Figure 2 but showing a modified form of the invention.

Figure 4 is a detail fragmentary sectional view through part of a pool table, triangle and pad, the same being on a reduced scale and positioned to illustrate how the balls are moved off the pad and into proper position for playing.

Referring to the accompanying drawing by numerals, 1 indicates a pool table of any desired kind having the usual table or body 2 and the side wall 3. In pool tables and also similar tables, it is customary to provide a cloth over the top of the table, said cloth being held in place by adhesive or other means whereby a smooth even surface is presented and one wherein there is a slight resistance to the movement of the balls. Where a triangle similar to the triangle 4 is used without a pad as shown in the accompanying drawing, the balls when being arranged in the triangle, will drop directly on the cloth 5 (Figure 4) of the table 2 and will wear the same more or less by reason of the impact. To obviate this wearing by reason of the dropping of the balls on the table

within the triangle 4, the pad 6 is provided which is constructed as shown particularly in detail in Figures 1 and 2. From these figures it will be noted that there is provided a body 7 and top and bottom covering members 8 and 9. The body 7 may be leather, leatherette or other desired flexible material while the covering members 8 and 9 are preferably cloth of the same kind as the cover or cloth 5. The body 7 extends from point 10 around one section of the triangle 4 and is connected together by a line of stitching 11. Point 10 is usually positioned substantially centrally of the height 70 of the triangle so that either edge of the triangle may be used and the pad swung to a position beneath the same as shown in Figures 1 and 2. When in this position, the various balls 12 may be dumped into the triangle 4 without any danger of in any way injuring the cloth 5 as the balls are caught by the cover 8 and the blow is cushioned by this cloth, by cloth 9 and the body 7.

After the balls have been placed in the triangle 4, the triangle is pushed along toward the place where the balls are to be left and as it is pushed it will assume the position shown in Figure 4 and if pushed further the triangle will be moved completely away from the pad 6 except for disconnection therewith by the looped extension 13. In order to prevent any buckling of any part of the pad, a series of lines of stitching 14 are provided, said lines being parallel as shown in Figure 4. 80 These lines of stitching act in the double capacity of holding the various members together and also in the capacity of presenting a weakened line or hinged formation whereby the pad will easily loop itself as shown in Figure 4 when the triangle 4 is pushed along over the table. When the triangle is not in use, the same may be hung on a hook or other support at any desired location.

In Figure 3, a slightly modified structure 100 is shown wherein the looped extension 13 merges at 14 into the body 15 which is similar to body 7. However, instead of having the top and bottom covering members in this form of the invention, there is provided only a single covering member 16 which is preferably used uppermost as shown in the drawing, though if the triangle was turned in the opposite direction it would be on the bottom and in contact with the cloth 5.

What I claim is:

1. A triangle pad comprising a body of

comparatively strong flexible material, a cover for said body, a series of lines of stitching extending across said cover and body for connecting the parts together and presenting 5 bending lines, and means for connecting said body at one end to one of the sides of the triangle said end being parallel to said bending lines.

2. A triangle pad comprising a flexible 10 body having an extension looped over one end of the triangle, means for connecting the

parts of the loop together, a cloth cover for the top and bottom of said body, said covering extending from said means to the free end of the body, and a series of lines of stitching for connecting said cloth covers to the body, said stitching also functioning as bending lines and extending parallel to that portion of the triangle over which said extension is looped. 15

FITCH C. IRVING.
